UNITED STATES PATENT OFFICE.

ERASTUS POND, OF PORTSMOUTH, OHIO.

APPARATUS FOR VAPOR BATHS.

SPECIFICATION forming part of Letters Patent No. 268,933, dated December 12, 1882.

Application filed September 26, 1882. (No model.)

To all whom it may concern:

Be it known that I, EERASTUS POND, of Portsmouth, in the county of Scioto and State of Ohio, have invented certain new and useful 5 Improvements in Apparatus for Vapor Baths; and I do hereby declare that the following is a full, clear, and exact description of the invention, which will enable others skilled in the art to which it appertains to make and use the 10 same, reference being had to the accompanying drawings, and to the letters of reference marked thereon, which form part of this specification.

My invention relates to improvements in 15 vapor baths, in which a table, supporting a revolving chair and having on its under side a deflector, is movable within a casing, in order constantly to be over an alcohol-lamp, notwithstanding the changes of the latter relative to 20 the casing; and the objects of my invention are, first, to converge the vapor on the upper part of the bather's body; second, to provide against the radiation of vapor; third, to concentrate the vapor on any side of the body; 25 and, fourth, to accomplish these objects with the greatest simplicity of construction.

My invention contemplates the cure of rheumatic and other diseases by the heat contained in vapors generated from an alcohol-lamp by 30 means of the apparatus shown on the accompanying drawings. It is always desirable to converge the vaporous waves upon the chest and lungs of the patient; and to this end I construct my bath with sloping sides terminating in a circular expansible neck-piece. All 35 the sides have an equal slope except the one behind, which forms a smaller angle, in order to follow the formation of the patient's back. It is also desirable to retain all the heat generated, and this I accomplish by having the 40 bath tightly closed and by providing the expansible impervious neck-piece, which will always form a tight joint with the patient's neck, regardless of its size, and yet not be so tight 45 as to be uncomfortable; I prefer rubber for this purpose. It is also frequently desirable to concentrate the vapor upon any part of the patient's body, and this I effect by placing the 50 chair on a table capable of horizontal reciprocation by moving the lamp and table, so that it may always be over a vapor-generating

lamp movable on the bottom of the bath; and, finally, it is always a desirable aim to attain to combine the maximum utility with the greatest simplicity, and this is one of the objects of 55 my invention.

In the accompanying drawings, Figure 1 is an elevation of the bath; Fig. 2, a central vertical section, and Fig. 3 a plan view of the bath, showing the expansible neck-piece. 60

Similar letters refer to corresponding parts throughout the specification.

The zinc-lined casing A has on its front side two doors, B G, the larger permitting the entrance and exit of the bather and the other 65 allowing the insertion and withdrawal of the lamp. The small door I prefer to make of glass to observe the operation. The table D is removable from place to place within the bath to suit the convenience of the bather or 70 the parts to which the bath may be applied. From its under side is suspended a deflector, E, preferably concavo-convex, and on its upper side is superposed a revolving chair, C. It will be readily understood that the chair can 75 thus always be brought over the lamp, regardless of its location, and that the deflector will serve to divide the vapor.

I am not aware that all these objects have before been attained in one apparatus, and 80 therefore

What I claim, and desire to secure by Letters Patent of the United States, is—

1. In a portab'e vapor bath, a sloping casing, A, provided with the two doors, B G, in 85 combination with the movable table D, a chair, C, and deflector E, all substantially as herein fully set forth and described.

2. In a portable vapor bath, the inclosing casing tapering at its apex, in combination 90 with a movable chair-support and chair and with a movable lamp, the said support and lamp being movable, in order to bring the vapor in contact with any desired part of the body, substantially as described.

In testimony that I claim the foregoing as my own I affix my signature in presence of two witnesses.

ERASTUS POND.
